UNITED STATES PATENT OFFICE.

WILLIAM C. BAXTER, OF ROCHESTER, NEW YORK, ASSIGNOR TO EDWARD M. TRIMBLE,
OF ROCHESTER, NEW YORK.

CRIB.

Application filed August 9, 1922. Serial No. 580,755.

To all whom it may concern:

Be it known that I, WILLIAM C. BAXTER, a citizen of the United States, and resident of Rochester, in the county of Monroe and 5 State of New York, have invented certain new and useful Improvements in Cribs, of which the following is a specification.

The present invention relates to cribs and more particularly to the type in which a 10 mattress supporting frame is adapted to be supported in a plurality of different horizontal positions, an object of this invention being to provide an improved upper position supporting means which will be inexpensive to manufacture, simple to operate, and strong and durable in use. A further object 15 of the invention is to provide a construction of simple operation which will permit the folding of the mattress supporting frame 20 in parallel relation with the side walls of a crib in which the side walls are movable toward each other for the purpose of folding the crib.

To these and other ends, the invention 25 consists of certain parts and combinations of parts, all of which will be hereinafter described: the novel features being pointed out in the appended claims.

In the drawings:

30 Fig. 1 is a vertical section through the crib constructed in accordance with this invention showing the mattress supporting frame in upper position;

Fig. 2 is a similar view showing the mattress supporting frame lowered at one end;

Fig. 3 is a view of the under side of the mattress supporting frame;

Fig. 4 is a plan view of the crib in folding condition;

Fig. 5 is a vertical transverse section 40 through the crib in folding condition;

Fig. 6 is a section on the line 6—6, Fig. 3;

Fig. 7 is a similar section showing the manner in which the operating handle for the upper position supporting means lies when the upper position supporting means is in operative position; and

Fig. 8 is an enlarged section on the line 7—7, Fig. 6.

45 Referring more particularly to the embodiment of the invention herein illustrated, 1 and 2 indicate two sides which are connected by end walls adapted to permit the sides 1 and 2 to fold toward each other in parallel relation. These end walls, in this

instance, each embody a rigid section 3 and two hinged sections 4 and 5, the hinged section 4 being hinged at 6 to the rigid section 3 to fold inwardly and the hinged section 5 being hinged at 7 to the hinge 60 section 4 and at 8 to the side wall 2. By this arrangement, when the end walls fold inwardly, space is provided between the sections 4 and the side wall 1 for the reception of the mattress and the mattress supporting frame.

The crib has a mattress supporting frame or member 9 which is adapted to be supported in two horizontal positions. The lower position supporting means, in this 70 instance, embodies a horizontal piece or side rail 10 and a horizontal piece or side rail 11, the horizontal piece or rail 10 connecting the rigid pieces 3 and the horizontal piece or rail 11 projecting inwardly from the side 75 wall 2 in a plane with the horizontal piece or rail 10. The mattress supporting frame 9 rests on these two pieces or rails when in its lowered position. The piece or rail 10 is of sufficient width to permit the mattress 80 supporting frame with the mattress 12 to be swung thereon as a pivot to the position shown in Fig. 5 in parallel relation with the side walls 1 and 2, a retaining lip 13 85 being provided at the edge of the piece 10 to prevent the mattress supporting frame slipping off the piece 10 in such turning or swinging movement.

This lower position supporting means permits the mattress supporting frame, in addition to being swung thereon, to be removed upwardly therefrom to an upper horizontal position. In order to support the mattress support in this upper horizontal position, two supporting members 14 are provided, 90 each, in this instance, formed of wire rod bent into U shaped form and pivotally connected to the mattress supporting frame near one end thereof. The pivoting is effected by turning one end of the U shaped member 95 inwardly at 15 and providing a lateral extending lug 16 on the other member, both of these pivots being secured in friction bearings formed by friction producing material such as a leather piece 17 and a bearing plate 18 secured by screws 19 passed through the bearing plate and the friction producing material 17.

In order that each support 14 may be operated from a point above the mattress sup- 110

porting frame, each **U** shaped member has at one end an extension 20, which is deflected inwardly from the adjacent end of the frame and has a grip piece 21 in the free end of said extension. This extension operates in a recess or notch 22 formed in the frame 9 adjacent said extension and the inner wall 23 of this notch serves to limit the outward swinging of the frame of the support 14. 10 The deflection permits the piece 21 to lie above the frame 9, while the support 14 is lying in parallel relation with the frame 9, as illustrated in Fig. 6.

In the use of the invention, the mattress 15 supporting frame, when in lower position rests upon the lower position supporting means 10 and 11. Should it be desired to fold the crib, the mattress supporting frame is swung on the piece 10, as a fulcrum, to 20 the position shown in Fig. 5, after which the end walls are folded inwardly in the manner shown in Figs. 4 and 5. Should it be desired to raise the mattress supporting frame while the crib is expanded, one end of 25 said frame is elevated and the handle 21 is operated to swing one of the upper position supporting members 14 outwardly at its lower edge. Thereafter the other end of 30 the mattress supporting frame is elevated and the lower edge of the other upper position supporting member is swung outwardly so that the parts finally assume the positions shown in Fig. 1. The friction bearings for 35 the upper position supporting members hold the latter against the under sides of the mattress supporting frame until they are shifted by the handles 21. This makes it possible to swing the mattress supporting frame to 40 an upright position, as shown in Fig. 5, without the upper position supporting members swinging on their pivots. The lowering 45 of the mattress supporting frame is

effected by reversing the operations which were necessary to move said mattress supporting frame to its upper supporting position. 45

From the foregoing it will be seen that there has been provided a crib in which a novel upper position supporting means is provided for the mattress supporting frame, 50 this upper position supporting means permitting the mattress supporting frame to be folded in parallel relation with the side walls. The upper position supporting members are operable from above the mattress 55 supporting frame and maintain their positions parallel with the bottom of the frame until shifted manually, so that they do not fall away from the frame when said frame is moved into parallel relation with the side 60 walls.

What I claim as my invention and desire to secure by Letters Patent is:

A crib comprising side walls, end walls connecting said side walls and foldable to 65 permit the side walls to move together in parallel relation, a mattress supporting frame, lower position supporting rails for said mattress supporting frame, and upper position supporting means embodying two 70 **U** shaped members, each having its arms pivoted to the mattress supporting frame and adapted to rest on said lower position supporting rails to sustain the mattress supporting frame in an elevated position, said 75 members having operating extensions projecting above the mattress supporting frame, and the mattress supporting frame having recesses through which said extensions project, one wall of each of said recesses acting 80 as a stop for engagement by an extension to limit the outward movement of the **U** shaped member on said support frame.

WILLIAM C. BAXTER.
